UNITED STATES PATENT OFFICE.

WILLIAM S. MILLS, OF FLORENCE, SOUTH CAROLINA.

GREASE-TRAP.

1,270,648.

Specification of Letters Patent. Patented June 25, 1918.

Application filed March 9, 1918. Serial No. 221,539.

To all whom it may concern:

Be it known that WILLIAM S. MILLS, a citizen of the United States, residing at Florence, in the county of Florence and State of 5 South Carolina, has invented certain new and useful Improvements in Grease-Traps, of which the following is a specification, reference being had to the accompanying drawings.

10 This invention relates to traps, and particularly to traps for catching and separating grease from water or other liquids draining from a sink.

The general object of the invention is to 15 provide a very simple and effective form of trap for this purpose, so designed as not to obstruct or impede the free flow of water from the sink.

A further object is to provide a construction of this kind including an outer body or casing which is intended to be permanently connected to the waste pipe of the sink and the waste pipe leading the sewer or other point of discharge, and to provide an interior strainer removable from the outer body or casing.

Still another object is to provide a strainer as referred to with means whereby it may be readily taken apart for cleaning, and further provide means whereby the interior strainer may be held in proper position within the outer casing or body so that the waste pipe may discharge thereinto.

Still another object is to so construct the 35 grease trap that the strainer may be readily removed, leaving the outer body or casing open for cleaning and to permit the strainer to be cleansed.

Still another object is to provide an auxiliary strainer disposed at the junction of the outer body or casing with the waste pipe leading to the sewer so as to catch any grease which may by any chance escape the main body of the trap, and provide means whereby this auxiliary strainer may be removed from the casing or body.

Other objects will appear in the source of the following description.

My invention is illustrated in the accompanying drawings, wherein:—

Figure 1 is a longitudinal sectional view of my improved grease trap;

Fig. 2 is a perspective view of the upper portion of the strainer; and

55 Fig. 3 is a vertical section of the auxiliary strainer.

Referring to these drawings, 10 designates the body of the trap, which is made of sheet metal or other suitable material, this body, for the greater portion of its length, being 60 uniformly tapered from one end to the other, the smaller end of the body being closed by a wall 11 and having leading therefrom a tubular connection 12 which may lead to the sewer or other point of discharge. The opposite end of the hollow tapering body or casing is downwardly flanged as at 13 and then continued to provide an annular wall 14, which is screw-threaded for engagement by the screw-threaded flange of a cover 15. 65 A waste pipe 16 leading from the sink enters the casing 10 adjacent the flange 13 at one point.

Removably disposed within the casing 10 is a grease strainer or catcher, which is 70 formed in two parts. One of these sections or parts comprises a tapering annular member 17 of imperforate metal, having an elongated opening 18 at one point therein. The other section 19 is formed of wire gauze or 75 like material and constitutes practically a tapering pocket closed at its lower end and provided with a handle 20. The gauze section 19 is connected to the section 17 by a screw-threaded union or joint 21 formed in 80 any suitable manner as by providing a metallic band at the large end of the section 19 having screw-threads which will engage screw-threads in the section 17.

At its upper end the section 17 is formed 85 with a flange 22, which is provided with notches 23 engageable with lugs 24 projecting upward from the flange 13. These notches and lugs are so arranged that when the lugs are engaged in the notches 23 the 90 opening 18 will be disposed immediately beneath the waste pipe 16, thus preventing such positioning of the strainer within the casing 10 that the waste pipe 16 will be out of line with the opening 18. A cover 25 detachably engages the large end of the member 17, the cover being provided with a suitable handle.

The small end of the casing 10, as before stated, engages with the waste pipe 12 and 100 at the junction of the waste pipe with the casing 10 or body I provide an auxiliary strainer 26 which is approximately hemispherical in form and formed of wire gauze, this strainer being mounted upon a rod 27 105 carrying at its upper end a plug 28 which has screw-threaded engagement with the

wall of the casing 10 and which is provided with a handle 29. The strainer may be held upon the rod 27 by reducing the extremity of the rod and screw-threading it for the reception of jam nuts 30. When the plug 28 is in place, the strainer is supported in the tapered entrance to the waste pipe, but this auxiliary strainer may be readily removed by unscrewing the plug and lifting the strainer out, the plug having a diameter equal to or slightly larger than the diameter of the strainer 26. The opening 18 not only permits the waste pipe to drain into the trap, but it provides means whereby the interior of the trap may be readily cleansed. This is further aided by the fact that the strainer is provided with a removable cover and that the two parts of the strainer are removable from each other.

20 By the use of my invention, provision is made for trapping or catching the grease which may pass through the waste pipe, so that the grease will not clog the pipes leading to the sewer, which is very liable to happen, and furthermore this does away with the necessity of cleaning these waste pipes when they become clogged, which is a very disagreeable job. Again by reason of the fact that the body 10 is inclined downward 25 and toward the waste pipe 12, all liquids passing into the trap will flow by gravity into the waste pipe and will not collect within the trap. Where water or other liquids collect within the trap, the liquid is very 30 liable to freeze thus bursting the trap or preventing the free flow of liquid through the same. Inasmuch as the opening 18 is relatively large in relation to the waste pipe 16, it will be obvious that there will 35 be no chance for water to pass down exteriorly of the strainer.

Preferably I form the waste pipe 12 to provide a trap 31 by bending the waste pipe upward and then downward and forward and a drain cock 32 is disposed in the trap thus formed. This trap will act to retain sufficient clear water in the outlet pipe 12 as to prevent foul gases from passing back from the sewer, this being required by sanitary regulations. By opening the drain cock 32 the water within the trap can be withdrawn to thus prevent freezing of the water in cold weather.

While I have illustrated a form of my invention which I have found thoroughly effective in practice and which may be used under widely varying conditions, yet it will be obvious that many changes may be made in the details of construction and combination and arrangement of parts, without departing from the spirit of the invention, as defined in the appended claims.

Having described my invention, what I claim is:

35 1. A grease trap of the character de-

scribed, comprising an exterior imperforate casing closed at one end and having a cover at the other end and having an inlet opening adjacent the last named end of the casing and an outlet opening adjacent the other end of the casing, and a grease strainer having an imperforate portion formed with an opening adapted to register with the inlet opening of the casing and with a wire gauze portion, the strainer fitting the interior of the casing.

2. A grease trap of the character described, including an outer casing tapered longitudinally and downwardly inclined and closed at its smaller end, a cover for closing the upper end of the casing, an outlet pipe leading from the small end of the casing, an inlet pipe leading into the side of the casing adjacent the large end thereof, and a strainer disposed within and fitting the casing having an imperforate portion provided with an opening adapted to register with the opening of the waste pipe and having a portion formed of wire gauze.

3. A grease trap of the character described comprising a tapered outer casing having an outlet at its small end, a cover closing the large end of the casing, the casing being formed with an inlet inward of the cover, a strainer removably disposed within and fitting the casing and having an elongated opening adapted to register with the inlet opening of the casing, and means permitting the removal of the casing but holding the casing from rotation and with its inlet opening registering with the inlet opening of the casing.

4. A grease trap of the character described comprising a tapered outer casing having an outlet at its small end, a cover closing the large end of the casing, the casing being formed with an inlet inward of the cover, a strainer removably disposed within and fitting the casing and having an elongated opening adapted to register with the inlet opening of the casing, and means permitting the removal of the casing but holding the casing from rotation and with its inlet opening registering with the inlet opening of the casing, and a cover fitting within the inlet end of the strainer.

5. A grease trap of the character described comprising a downwardly inclined casing tapering toward its lower end and formed at its lower end with an outlet pipe, the upper end of the casing being flanged and then extended upward and having a uniform diameter and being screw-threaded, a closure for the screw-threaded end of the casing, an inlet waste pipe opening into the casing below the flange thereof, and a strainer disposed within the casing comprising a conical body of wire gauze and an annular imperforate body having detachable engagement with the wire gauze body, said

imperforate portion being formed with a longitudinally extending inlet opening adapted when the strainer is in place to register with the inlet opening of the casing, 5 said imperforate portion of the strainer being provided with a flange fitting within the flanged portion of the casing, the flange and casing being formed with means permitting the removal of the strainer from the casing 10 but permitting the rotational movement of the strainer.

6. A grease trap of the character described comprising a tapered casing having an outlet extending adjacent its small end,

the small end of the casing being closed, a 15 strainer seating in the outlet pipe at its junction with the casing, a plug having screw-threaded engagement with the wall of the casing diametrically opposite the outlet pipe, and a rod extending from said plug 20 and connected to the strainer.

In testimony whereof I hereunto affix my signature in the presence of two witnesses.
